UNITED STATES PATENT OFFICE.

CHARLES SPRATT, OF NEW CROSS, AND FRANCIS JAMES SHENTON, OF THORNTON HEATH, ENGLAND.

SPEED-INDICATOR.

955,709.

Specification of Letters Patent. Patented Apr. 19, 1910.

Application filed March 8, 1909. Serial No. 482,100.

To all whom it may concern:

Be it known that we, CHARLES SPRATT, a subject of His Majesty the King of England, and resident of New Cross, in the county of Surrey, Kingdom of England, instrument-maker, and FRANCIS JAMES SHENTON, a subject of His Majesty the King of England, and resident of Thornton Heath, in the said county of Surrey, Kingdom of England, electrical engineer, have invented certain new and useful Improvements in and Relating to Speed-Indicators, of which the following is a specification.

This invention relates to speed indicators especially adapted for use in connection with motor cycles, motor cars, and machinery in general.

The object of the invention is to provide a device of the class described which is simple in construction, cheap to manufacture, and sensitive as well as positive in action.

A still further object of the invention is to provide an operating means for an indicator which will materially lessen the friction, and consequently the wear on the working parts, than has heretofore been done.

With these and other objects in view, the invention consists in the construction and novel combination of parts hereinafter fully described, illustrated in the accompanying drawing, and pointed out in the claims hereto appended; it being understood that various changes in the form, proportion, size and minor details of construction, within the scope of the claims, may be resorted to without departing from the spirit or sacrificing any of the advantages of the invention.

In the drawing:—Figure 1 is a front elevation of the device. Fig. 2 is a vertical sectional view through the same, showing some of the parts in elevation. Fig. 3 is a top plan view of the centrifugal regulator. Fig. 4 is a plan view showing a modified form of the spring, and Fig. 5 is a plan view showing the preferable construction of the spring. Fig. 6 is a detail sectional view taken through the sleeves and the operating rod.

The invention comprises a casing *c*, which is preferably tubular, and bent so that the opposite ends are arranged at right-angles to each other. Arranged within and closing one end of the said casing is an end cap *c*¹,

having an inwardly extending circumferential flange *c*², which bears against the casing and is retained in that position by means of set-screws *c*³, or other suitable fastening means. The end cap *c*¹ is provided with a central depending and integral sleeve *c*⁴ employed for a purpose hereinafter described.

The invention further comprises a cover *t*, which is provided with a circumferential flange *t*². This flange is preferably cut-out around its outer edge to form a seat, which is adapted to be positioned upon the circumferential flange *c*² of the end cap *c*¹ and thereby form a closed receptacle. The cover is furthermore provided with a central opening *t*³ which is in alignment with the sleeve *c*⁴ of the end cap. Arranged within the said sleeve *c*⁴ is a rod or shaft *f* which is connected to a rotary or flexible shaft *g*¹ or other transmission mechanism, said mechanism being adapted to receive its motion from any rotating or moving part of a machine. This rod extends within the beforementioned receptacle for a short distance, and has a reduced end *f*³ around which is secured a suitable bearing disk *f*¹ having a series of anti-friction balls *f*², or the like, arranged between it and the end cap *c*¹.

The invention further comprises a disk *d* which is provided with a central opening *d*¹, said disk being spaced from the bearing disk *f*¹ by anti-friction balls *u* and arranged above the same in such a manner that the reduced end *f*³ of the shaft *f* is arranged within the central opening *d*¹, the opening being of sufficient diameter to insure a free movement for the said disk *d*. The upper surface *h* is dished for a purpose herein-after described, and is provided at its outer upper edge with a circumferential cut-out portion *d*² adapted to form a seat for an upstanding flange or wall *e*. Arranged within the said wall *e*, and above the dished disk *d*, is a spider *j* which comprises a hub having a plurality of spaced and radially extending legs *j*¹, the connecting portions *j*² of the legs at the hub being curved. The upper surface of the spider is formed flat, and the under surfaces of the legs are shaped to conform to the shape of the dished disk *d*, as is clearly shown by reference to

Fig. 2 of the drawing. The spider is positively secured to the shaft f by set screw i which passes through the hub and into the reduced end f^3 of the said shaft. Thus it will be observed that the spider j and the bearing disk f^1 are carried by and rotated by the shaft, and the dished disk d , carrying the wall e , is loosely mounted with respect to the said shaft. Resting on the upper surface of the disk d and arranged between the radially extending legs j is a plurality of balls k , each having a diameter slightly greater than the depth of the spider.

Arranged to lie upon the balls k , and with 15 in the circumferential wall e , is a flat disk l , preferably made of steel, although other suitable material can be employed, if desired. Secured to this disk at its center, is an upwardly extending rod m which extends through the central opening t^3 of the cover t . This shaft extends above the said cover for some distance and is provided at its end with a rack-bar n . A sleeve y is arranged around the said shaft below the 20 rack-bar and is integral with the said cover t . This sleeve is provided near its lower end with a longitudinal slot p , and an additional sleeve x is arranged over the lower portion of the said sleeve, and is provided 25 with a pin p^1 , adapted to engage the rod m , and operate in the said slot. The upper end of the sleeve y is provided with a shoulder y^1 . Below and bearing against the said shoulder is a plate t^1 , which is held in position by means of an adjustable collar v and set-screw v^1 . Seated upon the upper edge of the small or outer sleeve x is a spring o . This spring is preferably formed as shown by Fig. 5 of the drawing, and is 30 formed of a flat piece of spring metal shaped to form a plurality of points. These points are curved upwardly and are adapted to bear against the underside of the plate t^1 .

A modified form of the spring is shown 45 in Fig. 4 of the drawing. The spring comprises a hub portion having a plurality of radially extending projections o^1 , between each two of which, is arranged a plurality of similar projections o^2 and o^3 respectively 50 of different lengths. It will thus be seen that while only three different sets of projections are shown in this figure, more can be employed equally as well if desired.

Suitably connected to the top t is a plurality of brackets q — q adapted to support a shaft r having a pinion q^1 mounted thereon, and arranged in a position to coact with the said rack-bar n of the rod m . A spiral spring s has one end fixed to the shaft r and 60 the other end to the plate t^1 . This spring is employed for a purpose hereinafter described. The shaft r is arranged at right-angles to the rod m and extends in a central

manner to the end a of the casing. The end a is provided with a suitable scale a^1 and the end of the shaft r is provided with a pointer b . A suitable lubricator cup w is arranged on the top of the casing c and is provided with a depending spout w^1 , the end of which is arranged directly above the rack-bar n in order that oil may be imparted to all the works in a very effective manner. A spring s^1 is employed and has one end secured to the shaft-supporting bracket by a screw or other suitable means s^2 , the other end adapted to 75 frictionally engage a portion of the shaft r for a purpose hereinafter described.

From the foregoing, it will be readily understood that the rotation of the shaft f carrying the spider will cause the balls to 80 travel in an outward and upward direction. The outward movement of the balls over the inclined or dished surface h of the disk d will elevate the disk l , and the rack-bar n which is carried by the rod m and elevated by the said disk l , will rotate the pinion q^1 on the shaft r and consequently move the pointer b . It will also be seen that the rod m and the outer sleeve x to which the spring o is attached, are prevented from rotating by the stud p^1 which connects the two parts together and passes through the guide-slot p in the inner sleeve y .

The spring o , against which the disk l moves, must be so graduated as to allow for 95 the variation of the centrifugal action at different speeds, so as to cause the pointer b to move uniformly on the scale. Should the modified form as shown in Fig. 4 of the drawing be employed, the first effort of the 100 disk l would depress the largest projection o^1 . As the speed is increased, the disk is elevated by movement of the balls, and the second series of projections o^2 will be acted upon in a like manner, and then, when the 10 speed is increased still further, the other or smaller set of projections o^3 will be likewise acted upon. It will also be observed that the disk d and the wall e thereof will not travel in accordance with the spider j , 11 as there will be a certain play of the disk d at different speeds, thus preventing the balls k from traveling in the same path, and thereby lengthening the life of said parts by lessening the wear in any one place. The coiled 115 spring s is more sensitive than the spring o , and therefore, slight movements are better indicated with its use, as will be well understood. The spring s^1 which bears against portion of the shaft r tends to dampen any 12 unnecessary vibrations and prevents flickerings of the pointer.

What we claim is:

1. In a speed indicator, the combination with a casing having a pointer rotatably mounted at one side thereof, of a shaft ar-

ranged within the casing and provided with a ball-carrying receptacle, and means for communicating motion to the pointer from the balls within said receptacle upon the 5 rotation of the shaft.

2. In a speed indicator, the combination with a casing having a pointer rotatably mounted at one side thereof, of a shaft arranged within the casing and provided 10 on its end with a dished disk, a spider carried by the shaft and arranged within the disk, a plurality of balls carried by the disk and spaced from each other by the spider, and means for rotating the pointer, said 15 means having a part which is arranged to rest on the balls and to be actuated by the outward and consequent upward movement of the said balls upon the rotation of the said shaft.

20 3. In a speed indicator, the combination with a casing having a pointer rotatably mounted at one side thereof, and a closed receptacle arranged within the other end, a shaft arranged to extend within the 25 receptacle and provided at its end with a loosely mounted ball-carrying receptacle having an outwardly inclined upper surface, a spider carried by the shaft and arranged within the receptacle and between the balls 30 and spacing the latter, and a disk resting upon and supported by the balls and provided with means for actuating the pointer upon the rotation of the shaft and spider and the consequent rotation of the said balls.

35 4. In a speed indicator, the combination with a casing having a pointer rotatably mounted at one side thereof and a closed receptacle at another side, of a shaft arranged to extend within the said receptacle and 40 provided at its end with a ball-carrying and rotating means including an outwardly and upwardly inclined upper surface, a shaft for the pointer provided with a pinion, and a disk adapted to lie on the balls and having 45 a rod provided with a rack-bar adapted to engage the said pinion, and thereby rotate the pointer upon the outward and upward movement of the balls when the first-mentioned shaft is rotated.

50 5. In a speed indicator, the combination with a casing having a pointer rotatably mounted at one side thereof, of a shaft arranged within the casing, a receptacle loosely mounted on the shaft and comprising 55 a bearing disk having an outwardly and upwardly inclined upper surface, a spider arranged within the receptacle and fixed to the shaft, a plurality of balls arranged within the receptacle and spaced apart by the spider, another disk arranged at the top of the receptacle and independent of the shaft, and means for rotating the pointer, said 60 means being connected to the last-mentioned

disk which rests upon the balls, and said means being adapted to be actuated by the 65 outward and consequent upward movement of the balls upon the rotation of the said shaft.

6. In a speed indicator, the combination with a casing having a pointer rotatably 70 mounted at one side thereof, and a closed receptacle arranged within the casing at another side, of a shaft arranged to extend within the said receptacle and provided at its end with a loosely mounted ball-carrying 75 disk having an outwardly and upwardly inclined upper surface, a shaft adapted to rotate the pointer and provided with a pinion, an inner sleeve arranged on the closed receptacle and below the pinion and provided 80 with a slot in one end thereof, a plate rigidly secured around the said sleeve at one end, and an outer sleeve arranged on the other end thereof and provided with a pin adapted to pass through and beyond the slot of the 85 inner sleeve, a spring supported by the outer sleeve and adapted to bear against the said plate, a disk arranged within the receptacle and adapted to rest upon the balls, a rod extending from the disk and within the said 90 inner sleeve, said rod being fixed to the outer sleeve by the said pin, a rack-bar extending beyond the end of the inner sleeve and adapted to engage the pinion, the outward and consequent upward movement of the balls 95 upon the rotation of the shaft being adapted to elevate the disk and rack-bar against the spring and thereby rotate the pointer-carrying shaft.

7. In a speed indicator, the combination 100 with a casing having a pointer rotatably mounted at one side thereof, and a cap arranged at another side, said cap having an outstanding sleeve, of a shaft having a reduced inner end arranged within the said 105 sleeve and extending within the casing beyond the cap, a bearing disk loosely mounted on the reduced end of the shaft and having an outwardly and upwardly inclined upper surface, a spider arranged above the disk 110 and carried by the shaft, said spider comprising a hub portion having a plurality of radially extending legs, a plurality of balls arranged on the said disk and spaced apart by the legs of the spider, a cover for the said 115 cap arranged within the casing, a second shaft adapted to rotate the pointer and provided with a pinion, a sleeve arranged on the cover and below the pinion and provided with a longitudinal slot, a plate rigidly secured around the sleeve at one end, an outer sleeve arranged on the other end thereof and provided with a pin adapted to pass through and beyond the slot of the inner sleeve, a spring supported by the outer sleeve and 120 adapted to bear against the said plate, a 125

second disk arranged within the receptacle and adapted to rest upon the balls, a rod extending from the said disk and arranged within the said inner sleeve, said rod being 5 fixed to the outer sleeve by the said pin, a rack-bar extending beyond the end of the inner sleeve and adapted to engage the pinion, whereby an outward and consequent upward movement of the balls upon the rotation of the shaft is adapted to elevate the 10

disk and rack-bar against the spring and thereby rotate the pointer-carrying shaft.

In testimony, that we claim the foregoing as our invention, we have signed our names in presence of two subscribing witnesses.
